US00D500964S

(12) **United States Design Patent** (10) Patent No.: **US D500,964 S**
Lach (45) Date of Patent: **** Jan. 18, 2005**

(54) **CIRCULAR SHAPED KINETIC SCULPTURE**

(75) Inventor: **Robert L. Lach**, Cincinnati, OH (US)

(73) Assignee: **Source Advantage Ltd.**, Cincinnati, OH (US)

(**) Term: **14 Years**

(21) Appl. No.: **29/185,569**

(22) Filed: **Jun. 30, 2003**

(51) LOC (7) Cl. **11-02**

(52) U.S. Cl. **D11/131; D11/141**

(58) Field of Search **..... D11/1, 2, 43, 45, D11/79, 85, 86, 89, 90, 121, 125, 131, 141, 164, 184; D10/54, 59, 116, 119, 121; D6/580, 581; D26/138, 154; D17/99; D21/455, 458, 459, 465, 466, 467; D22/120; D23/411; 428/7-13, 20, 27, 28, 31, 542.2, 542.4, 542.6; 40/409, 411-413, 421, 422, 427, 439-441, 477, 479, 480, 484, 492-495, 559-562, 582, 617; 446/199, 201, 217, 218, 236, 238, 241, 243, 244, 487, 490; 16/216-218; 362/457, 806; 160/330, 332, 384, DIG. 6**

(57) **CLAIM**

The ornamental design for a circular shaped kinetic sculpture, as shown and described.

DESCRIPTION

FIG. 1 is a perspective view showing my new design for a circular shaped kinetic sculpture;

FIG. 2 is a front elevational view thereof, the rear view being identical thereto;

FIG. 3 is a right side elevational view thereof, the left side view being identical thereto;

FIG. 4 is a top plan view thereof;

FIG. 5 is a bottom plan view thereof;

FIG. 6 is a perspective view of an alternate embodiment of my design;

FIG. 7 is a front elevational view thereof, the rear view being identical thereto;

FIG. 8 is a right side elevational view thereof, the left side view being identical thereto;

FIG. 9 is a top plan view thereof; and,

FIG. 10 is a bottom plan view thereof.
